UNITED STATES PATENT OFFICE.

JOHN A. THOMPSON, OF HOWARD, KANSAS.

WINDOW-SHADE HANGER.

SPECIFICATION forming part of Letters Patent No. 508,783, dated November 14, 1893.

Application filed June 6, 1893. Serial No. 476,754. (No model.)

To all whom it may concern:

Be it known that I, JOHN A. THOMPSON, of Howard, in the county of Elk and State of Kansas, have invented a new and Improved Window-Shade Hanger, of which the following is a full, clear and exact description.

My invention relates to an improvement in window shade hangers, and it has for its object to provide a simple device capable of attachment to any window frame, whereby a window shade and its brackets may be raised or lowered in a convenient and expeditious manner, so as to leave any portion of the upper or lower half of a window opening uncovered, and whereby also the shade may be placed whenever desired, in its ordinary position at the top of a window frame; and whereby further no matter in what position the shade may be placed it may be manipulated as readily as when hung in the usual manner.

The invention consists in the novel construction and combination of the several parts, as will be hereinafter fully set forth and pointed out in the claims.

Reference is to be had to the accompanying drawings forming a part of this specification, in which similar figures and letters of reference indicate corresponding parts in all the views.

Figure 1 is an inner face view of a window frame, illustrating the application of the device thereto, and showing the window shade as located near the bottom of the upper half of the window. Fig. 2 is a front elevation of the shade carriage. Fig. 3 is a plan view of the shade carriage; and Fig. 4 is a perspective view of the slide section of the carriage.

The invention consists of a strip or slat 10, which may be made from any material, and may be plain or ornamental and may be of any desired shape. Ordinarily, however, the strip or slat, as its name implies, is made rectangular in cross section, and is practically of a width corresponding to the diameter of a rolled shade, while the length of the strip or slat is such that it will extend from one side of the window frame to the other. A guide rod 11, is located longitudinally at each side of the window frame. The upper portion of each rod is secured by means of a screw, or like fastening device, to the upper or top section

of the window frame, usually where it connects with the sides, and the said guide rods extend perpendicularly downward and terminate at any desired point in the length of the sides, usually below the center of the window frame. The lower ends of the rods are ordinarily attached to the frame through the medium of staples 12, or like devices, the attachment being so made that a space of predetermined width will intervene the window frame and the opposing surface of the rods.

Brackets 13 of any approved construction, adapted as journals for the shade roller, are secured to the strip or slat 10, ordinarily near each end thereof; and a slide A, is located at each end of the strip or slat 10, said strip or slat and the slide constituting a carriage for the shade.

The slide is preferably made of wire, and in its construction the wire is bent upon itself to form two loops 14 and 15, which loops are at angles to each other; and where the loops connect a coil 16, is formed in the wire. One of the loops, that which may be termed the outer one 15, is usually reinforced at its longer or vertical portion or section by a second stretch 17 of wire, the second stretch 80 running parallel with the said longer vertical section of the loop; and the ends of this auxiliary stretch of wire may be coiled around the horizontal or upper and lower sections of the said loop.

The slides are applied in the following manner: Prior to securing both of the ends of the guide rods 11, each rod is passed through the coil 16 of a slide section, the said section having sliding and guided movement upon the rods through the medium of the said coils. The ends of the slat or strip 10, are then passed through both of the loops, the back of the strip being in engagement with the guide rods, and being held in comparatively close engagement by the spring action of the loops, which loops cross the upper and lower and front faces of the strip; and the slide sections are preferably so located upon the strip or slat 10, that a curtain bracket 13, will be located between the loops, as shown in both Figs. 2 and 3. The frictional engagement between the slide sections of the slat and the guide rods is sufficient to hold

the slat in whatever position it may be placed, against the tension exerted upon it by the rolling and unrolling of the shade; but the frictional engagement is so made that by drawing downward or pushing upward upon the slat 10 it may be conveniently raised or lowered, or carried to any point across the window between the top and bottom portions of the guide rods. To facilitate the movement of the shade carriage, a handle 18, is usually projected downward from the central portion of the slat, as shown in Fig. 1.

It is obvious that by means of this attachment the shade may be readily raised and lowered so as to expose any desired portion of the upper or lower half of the window, or to cover any desired portion; or that if desired the shade may be made to cover the entire window opening in the ordinary way.

Having thus described my invention, I claim as new and desire to secure by Letters Patent—

1. A window shade hanger, comprising guides adapted to be secured to a window frame, a shade roller carrying bar, and slides fitted to slide on the guides and provided with spring loops for receiving and holding the ends of the said bar, substantially as described.

2. A window shade hanger, comprising guides adapted to be secured to a window

frame, a bar provided with shade roller bearings, and slides fitted to slide on the guides and to be adjustably held thereon by frictional contact, said guides being provided with loops between which and the guides the ends of the said bar project, substantially as described.

3. As an improvement in window shade hangers, the combination, with guides adapted for attachment to the window frame, of connected loops arranged at angles to each other and having sliding engagement with the guides, and a bar adapted to receive the shade roller bearings, which bar is passed through the loops, supported thereby and held in engagement with the guides, as and for the purpose specified.

4. As an improvement in window shade hangers, guides adapted for attachment to the window frame, slides comprising loops arranged at angles to each other and provided with eyes at their junction, through which the guides pass, and a slat or bar adapted to carry the bearings of the shade roller, which slat or bar is passed through the loops of the slides and held in frictional engagement with the guides, as and for the purpose specified.

JOHN A. THOMPSON.
